[57] CLAIM

The ornamental design for a fly rod holder, as shown and described.

DESCRIPTION

FIG. 1 is a top right side perspective view of a fly rod holder showing my new design, with a fly rod and straps in phantom;

FIG. 2 is a top plan view thereof;

FIG. 3 is a right side elevation view thereof;

FIG. 4 is front elevation view thereof;

FIG. 5 is a rear elevation view thereof;

FIG. 6 is a left side elevation view thereof; and,

FIG. 7 is bottom plan view thereof.

The phantom line disclosure in FIG. 1 of a portion of a fly rod inserted into the fly rod holder and of a portion of hold-down straps is for illustration purposes only and forms no part of the invention.
